ATTORNEY.

UNITED STATES PATENT OFFICE.

BÖRGE CEDERLÖF, OF STAVANGER, NORWAY.

MANACLES, HANDCUFFS, AND THE LIKE.

Application filed February 24, 1925. Serial No. 11,247.

To all whom it may concern:

Be it known that I, BÖRGE CEDERLÖF, a subject of the King of Norway, residing at Stavanger, Norway, have invented certain new and useful Improvements in Manacles, Handcuffs, and the like; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to new and useful improvements in manacles, such as are used by the police to grasp and lead prisoners from place to place, or which may be used as a handcuff or handfetter to chain one prisoner to another.

It is the object of my invention generally to improve the construction of devices of this kind and my invention resides and consists in the novel construction and combination of parts shown upon the accompanying drawing forming a part of this specification, upon which similar characters of reference denote like or corresponding parts throughout the several figures and of which:—

Fig. 1 is a view of my manacle in an upright position with the jaws in an open position but shown in a closed position in dotted lines.

Fig. 2 is an end view of my manacle in an upright position.

Fig. 3 is a sectional plan view on the line A—B in Fig. 1.

The jaws 1 and 2 are pivoted on pins 3 and 4 in the holder 5 and are extended to form short arms 6 and 7 which are connected to lugs on a nut 10 by the pins 8 and 9.

The holder 5 and the nut 10 are connected to each other by a screw 11 provided with a handle 12.

The screw 11 has square threads of rapid pitch for instance 4 threads per inch, and the thread may most conveniently be left handed.

On the lower part of the screw 11 where the nut 10 operates small threads are cut upon the square threads and are conveniently of opposite hand to the square threads.

In the screw 11 a longitudinal slot 13 is

cut for the reception of a plate 14 which may be serrated at the edges as shown and acts as a pawl or detent engaging in the notches 15 formed in the holder 5, the pawl 14 being pressed towards the notches by a spring 20 housed in a slot 19 in the pawl 14 into which it is conveniently inserted through an opening in the handle 12 and kept in place by a grub screw 21. The part of the pawl 14 which engages the notches 15 is bevelled on one face to permit the screw to turn in the direction in which the closing of the jaws 1, 2 is effected while locking the screw against backward rotation and the jaws against opening. An auxiliary locking catch 17 provided with a handle 16 is arranged in an inclined guide groove 18 in the pawl 14 and slides therein transversely of the screw 11. This pawl, when projected, will engage in an aligned notch 15 and since these notches extend entirely around the holder, the screw 11 and accordingly the jaws 2 may be locked in any desired position.

In order to release the jaws the pawl 14 is moved out of engagement by hand against the action of the spring 20, the projecting serrated edges of the pawl affording convenient gripping surfaces.

Having now particularly described and ascertained the nature of my said invention and in what manner the same is to be performed, I declare that what I claim is:—

1. The improved manacles comprising a holder, pivoted jaws adapted to be adjusted and locked in different positions in said holder and having short arms or extensions pivotally connected with a nut, a screw spindle with threads of opposite pitch engaging the nut and holder, said holder having notches, a spring-pressed pawl guided in a slot in the screw spindle and arranged to co-operate with notches in the holder to lock the screw and jaws against movement in one direction and an auxiliary locking catch guided in the pawl and capable of being moved into engagement with the notches in the holder to lock the jaws of any of a plurality of positions, substantially as described.

2. The improved manacles comprising a notched holder, a nut, pivoted jaws adapted to be adjusted and locked in different positions in a holder and having short arms or extensions pivotally connected with the nut, a screw spindle with threads or opposite

pitch engaging the nut and holder and a spring pressed pawl guided in a slot in the screw spindle and arranged to co-operate with notches in the holder to lock the screw and jaws against movement in one direction.

3. The improved manacles comprising a notched holder, a nut, pivoted jaws adapted to be adjusted and locked in different positions in a holder and having short arms or extensions pivotally connected with the nut, a screw spindle with threads of opposite pitch engaging the nut and holder and a spring pressed pawl guided in a slot in the

screw spindle and arranged to co-operate 15 with notches in the holder to lock the screw and jaws against movement in one direction, said pawl being in the form of a plate disposed within the slot and having portions of its edges projecting at opposite 20 sides thereof, said projecting edges being knurled to afford a gripping surface whereby the pawl may be withdrawn against the action of its spring.

In testimony that I claim the foregoing 25 as my invention, I have signed my name.

BÖRGE CEDERLÖF.
